UNITED STATES PATENT OFFICE.

WILLIAM N. CAVILEER AND RUTH L. CAVILEER, OF RAY, ARIZONA.

ROTARY TOOTHBRUSH.

1,351,159.

Specification of Letters Patent. Patented Aug. 31, 1920.

Application filed March 27, 1917. Serial No. 157,734.

To all whom it may concern:

Be it known that we, WILLIAM N. CAVILEER, and RUTH L. CAVILEER, citizens of the United States, residing at Ray, in the county 5 of Pinal and State of Arizona, have invented new and useful Improvements in Rotary Toothbrushes, of which the following is a specification.

The present invention contemplates the 10 production of a tooth brush of the rotary type, which can be effectively used to cleanse the teeth and remove particles of foreign matter accumulating between the crevices of the teeth, and further so constructed as to be 15 readily manipulated and retained in a clean and sanitary condition at all times.

An object of the invention resides in the provision of a novel type of brush of the above stated character, wherein the handle 20 portion thereof is provided with a shaft on which the brush body is mounted for free rotary movement permitting of the brush body to be actuated during the cleansing operation of the teeth.

25 With the above and other objects in view, the invention consists in the novel features, details of construction and combination of parts which will hereinafter be more fully set forth, illustrated in the accompanying 30 drawing and pointed out in the appended claim.

Figure 1 is a perspective view of the brush constructed in accordance with the present invention;

35 Fig. 2 is a side elevation of the brush showing the brush body removed therefrom; Fig. 3 is a perspective view showing a slightly modified form of brush body;

40 Fig. 4 is a perspective view of a still further modified form of brush body;

Referring more particularly to the accompanying drawing, in which like characters of reference refer to corresponding parts in the several views, and reference being had 45 more particularly to the form of brush illustrated in Figs. 1 to 4 inclusive, 5 denotes a handle constructed of any suitable material and provided with an opening 6 to permit the brush being suspended from a suitable 50 support (not shown). Extending axially of the handle 5 and projecting beyond the inner end 7 thereof, is a cylindrical shaft 8. The shaft in this particular form of brush is illustrated as constituting a stub shaft 55 which projects within the hollow core 9 of the brush body 10. Formed contiguous with the end 7 of the handle and in a plane with

one face of the handle is a resilient backing 11 of substantially L-shaped form. The vertical portion 12 of the L-shaped backing 60 is terminally provided with an inwardly extending circular trunnion 13 adapted to project in the opposite end of the hollow core 9 of said brush body, hence supporting the brush body 10 of the handle for a free 65 rotary movement. It is obvious that, by providing the back 11 of a resilient nature, the flexing of the back outwardly releases the trunnion 13 from the hollow core 9 of said brush body and permits the removal 70 of the brush body from the shaft 8. This type of construction not only serves to mount the brush body in the manner previously stated, but further serves to retain the brush body on the shaft 8 of the handle. 75 The brush body shown associated with the brush in Fig. 1 of the drawing as well as the modified form of brush bodies disclosed in Figs. 3 and 4 thereof, comprises bristles 14 secured to the core 9 and arranged in 80 spaced spiral form, to provide between the bristles a continuous spiral groove 15.

From the foregoing description, taken in connection with the accompanying drawing, the advantages of construction and the 85 method of operation will be readily apparent to those skilled in the art to which the invention relates, and while we have described the principles of operation of the invention, together with the device which 90 we now consider to be the best embodiment thereof, we desire to have it understood that the device shown is merely illustrative and that such changes may be made when desired as are within the scope of the appended 95 claim.

Having thus described the invention, we claim:

A brush embodying a rigid handle provided at one end with an L-shaped resilient 100 backing, a shaft having one end fixed in the handle and disposed below and in parallelism with the horizontal portion of said backing, a brush body mounted on said shaft, and means for detachably connecting 105 one end of the brush body with the vertical portion of the backing and preventing any accidental displacement of the brush body therefrom.

In testimony whereof we affix our signatures.

WILLIAM N. CAVILEER.
RUTH L. CAVILEER.
